CLAIM

The ornamental design for a support for mounting radios in a vehicle having bench seats, as shown and described..

DESCRIPTION

FIG. 1 is a front perspective view of a support for mounting radios in a vehicle having bench seats showing my new design it being understood that the broken lines are for illustrative purposes only;

FIG. 2 is a side elevation view thereof, the opposite side being a mirror image of that shown; and

FIG. 3 is a front elevation view thereof.

The two rear horizontal panels of the support are understood to be flat and unornamented.

FIG.1

FIG.2

FIG.3
